PAINT PAIL

James D. Cole, Austin, Tex.

Application December 17, 1957, Serial No. 48,938

Term of patent 14 years

(Cl. D58—17)

Fig. 1

Fig. 2

Fig. 3

Fig. 1 is a perspective view of a paint pail showing my new design.

Fig. 2 is a perspective view taken from above and to the front on a reduced scale.

Fig. 3 is a side elevational view thereof on a reduced scale taken from the opposite side to that shown in Fig. 1.

The rear of the pail is plain.

I claim:

The ornamental design for a paint pail, substantially as shown and described.
